UNITED STATES PATENT OFFICE.

GEORGE W. DONNING, OF EAST ORANGE, NEW JERSEY, ASSIGNOR TO
HARRY T. AMBROSE, OF ORANGE, NEW JERSEY.

TYPE-WRITING MACHINE.

No. 826,482.

Specification of Letters Patent.

Patented July 17, 1906.

Application filed September 23, 1901. Serial No. 76,288.

To all whom it may concern:

Be it known that I, GEORGE W. DONNING, a citizen of the United States, residing at East Orange, in the county of Essex and State of New Jersey, have invented certain new and useful Improvements in Type-Writing Machines; and I do hereby declare the following to be a full, clear, and exact description of the invention, such as will enable others skilled in the art to which it appertains to make and use the same.

This invention has reference primarily to table-tops for sustaining large books—such as books of record, ledgers, dictionaries, and the like and particularly to that class of type-writing machines in which a downward-acting writing mechanism is used in connection with a platen to sustain the leaf of a book having its body supported and movable below and independently of the platen.

The invention is susceptible of many applications and embodiments. One embodiment thereof consists in the combination, with the platen, which stands normally at rest, of a book-support arranged to be moved at will beneath the platen and comprising vertically-yielding leaves or boards adapted to underlie and support the two sides of the book, so that one side or the other of the book may be brought in position to permit a leaf to be turned over and supported upon the platen while being printed upon by the movable writing-machine, and this regardless of the thickness of the book and of the variation in thickness between the two sides. As stated, the platen may stand normally at rest and the carriage and its basket may be mounted at a fixed height and the book-support be movable longitudinally, transversely, or otherwise. The platen may likewise be at a fixed height, as in the case of the basket and its carriage. The whole device may, if desired, all be placed in one table. This book-support may also be used for supporting the platen or platens to be used in conjunction therewith and may extend the entire length and breadth thereof, so that a metal of light weight or thinness may be employed and yet the platen be fully supported and be prevented from sagging, thus maintaining the platen or platens true to the printing-point at any position or location of the carriage or basket. Moreover, the book-rest would aid materially in deadening any

sound arising from impact of the type upon the platen. In the event that a bound book is used the leaves and cover thereof resting under the platen can be maintained closely under the platen, this aiding in deadening the sound, or where loose sheets are used the supports may be held up against the platens in the same manner and prevent noise.

Referring to the drawings, Figure 1 is a view in perspective, showing my sliding top, the book-supporting mechanism, and a book thereon in connection with the platen. Fig. 2 is a view in vertical section lengthwise of the book. Fig. 3 is a view in transverse vertical section with the various parts in their operative positions. Fig. 4 is a similar section through the book-support alone, illustrating the change in the relation of its two sides to compensate for the variation in the relative thickness of the two sides of the book. Fig. 5 is a vertical section on the line 5—5, Fig. 7. Fig. 6 is a view in end elevation thereof. Fig. 7 is a view in plan. Figs. 8 and 9 are detail views. Fig. 10 is a view in perspective of the longitudinally and transversely movable book-support.

Referring to the drawings, A designates a table or bed to sustain the type-writing mechanism, platen, and the book-support, hereinafter more particularly described. This table may be constructed with its surface of flat or other suitable form; but it is preferably constructed with a longitudinal depression or channel *a* to receive and guide a book-supporting device B, presently to be described. It is to be understood that the depression or channel *a* may run lengthwise of the table, if desired, to permit the book-support B to be moved longitudinally, or there may be a supplemental base movable longitudinally, so that the book-support may be moved transversely and its supporting medium be moved longitudinally, or the supplemental base may move transversely and the book-support longitudinally, as shown in Fig. 10. In this figure, which may be regarded as being in some degree diagrammatic, B¹ is the frame of the book-support movable transversely by reason of rollers b¹ and bearing the rising and falling book-supporting leaves J J¹. B² is the supplemental frame on which run rollers b² and which is itself longitudinally movable on the table-top through rollers b²¹. b²² represents racks

formed on the under sides of the longitudinal members of the supplemental frame. b^{23} represents pinions meshing with racks b^{22} and carried by shaft b^{24} , and b^{25} is a pawl carried by lever b^{26} for operating pinions b^{23} . The relation of these structures to the underlying idea of my invention will be more readily apparent from the following consideration of the other figures.

- 10 In the channel or depression a of the table is a frame B^2 , adapted to move freely therein and preferably flat and rectangular in shape, though it is to be understood that it may be of any construction and shape, the 15 point being to have a base movable at will, as presently to be described, and capable of carrying mechanism for supporting a book to be written upon. To strengthen the frame, I may, if desired, have across the central portion thereof a brace or beam b . At 20 the sides of the frame B^2 , preferably at the four ends and at the center, are rollers or small wheels b^2 , preferably flanged, which bear, preferably, upon tracks b^3 , lying along 25 the sides of the channel a and secured to the table, or the tracks may be dispensed with and the rollers run on the depressed part of the table, as shown in Figs. 1 and 2. If desired, suitable stops or cushion devices may 30 be located at the ends of the depression, against which the frame may strike, and these may be adjustable, if desired. It is to be understood, however, that these rollers or wheels b^2 may be located at any other appropriate 35 portion of the device, as in the lower face of the frame B^2 , or, if desired, in the floor of the channel, so that the frame may roll upon the same. Likewise the same could be long rollers or balls countersunk in the floor 40 of the channel, as is obvious, the important consideration being to afford means by which the frame may freely and quickly move in the channel a . The parts just described constitute what I designate a "sliding-top" table. With this I may employ 45 what I term my "adjustable" book-rest, the same forming generally an essential adjunct to my sliding-top table. The preferred arrangement of this book-rest is illustrated in 50 Figs. 3, 4, 5, 6, 7, 8, and 9.

In the two front corners of frame B^2 are located upright plates I and in the rear corners similar plates I^2 . Pivoted near the upper ends of plates I are upwardly and inwardly extending arms i^1 . Similar arms i^3 are pivoted near the upper ends of rear plates I^2 , and a second pair of upwardly and inwardly extending arms i^4 are pivotally mounted near the lower ends of these rear 60 plates. The inner ends of arms i^1 are pivotally secured to short standards i^5 , depending from the forward portions of book-supporting leaves J J^2 , while the inner ends of arms i^3 i^4 are pivotally secured to long standards i^6 i^8 , depending from the rear portions of the 65

leaves. It will be understood that the arms are so constructed and mounted as to be parallel at all times, whereby uniform vertical movement of the book-supporting leaves is insured. The arms may, if desired, be of sufficient resiliency to give a springy yielding effect to take up jar and noise. In order to insure synchronous movement of arms i^1 i^3 at each end of the book-support and to prevent any tendency of the leaves to cant and stick, 75 I may connect such pairs of arms by rods l^1 , rigidly secured thereto and extending from front to back of frame B^2 .

Pivots connecting the standards i^6 , so as to adapt leaves J J^2 to move in opposite 80 vertical directions, is a rocking plate K of any requisite form. This plate is provided at its ends with slots i^{11} , which receive the pivot-pins i^9 , projecting from standards i^6 , and thus permit the necessary play between 85 the standards and the plate. Preferably there is but one of these rocking plates to connect the rear standards i^6 at the back, it not being essential to connect the front standards in this manner, though it is to be understood that I may do so, if required. Normally this rocking plate is in a horizontal position, the arms i^1 and parallel arms i^3 i^4 i^6 i^8 inclining upward from their pivotal point in the corner-plates I , thus holding the standards in movable vertical suspension. 90

Each vertical yielding leaf J J^2 works in harmony with the other through the medium of the rocking plate K and adjusts itself properly to position the parts as the leaves of the 100 book are turned from one side to the other. It is obvious that as one side of the book becomes heavier the yielding leaf on that side will become depressed, and this in turn depresses its sustaining parts. At the same 105 time the opposite side will rise automatically to the same extent to which the other is depressed. If the leaves of each side of the book are about evenly distributed, the weight on each leaf will be nearly equal, and it may 110 then become necessary for the operator to adjust the device by hand to bring the book-leaves close to the platen. These movements are of course in harmony with the other parts of the device. By having the parts 115 at the front of the work-support of less depth than the rear I am able to employ a lower table-frame, since when one or other of the leaves is depressed the front standard i^6 and arms i^1 never drop below the front frame of 120 the table, though the rear standards i^6 and the supporting-arms i^4 i^6 may. By this arrangement the parts of the device will not contact with the body of the operator, and the writing mechanism may thus be mounted 125 lower than would otherwise be possible, facilitating easy manipulation of the parts.

I may desire to provide means located, preferably, centrally of the rocking plate by which to effect certain and regular move- 130

ment of the standards. A preferred form is that illustrated in Fig. 5, consisting of plates L, one of which is supported on a bracket l, attached to the rectangular skeletal frame 5 B². There are preferably two of these plates L, suitably shaped and connected at their lower portion, as by bolts l³, passing through perforations l⁴. These plates L are provided centrally with a vertical slot l⁵, in which slides 10 a pin l⁶. Interposed between these plates and extending, preferably, from the top line thereof nearly two-thirds of their length are preferably two cam-plates M, one edge m of each of which is straight, while the other edge m² is rounded and provided with teeth m³, which are designed to mesh with similar teeth n in two pinions N, located, preferably, below the cam-plates, and which are carried by a spindle n², extending through the plates 15 L and the pinions N and to the front of the device, the projecting end being provided with a small wheel n³, against which may, if desired, bear a friction-clutch knob n⁴. The spindle may be provided at the points where 20 it passes through the plates L and between the pinions N with collars n⁵. In the upper portion of the cam-plates M is a perforation in which fits the sliding pin l⁶, above referred to. Between the two cam-plates M is inter- 25 posed the rocking plate K, which at its central portion is provided with a perforation through which passes the sliding pin l⁶, carried by the cam-plates M and sliding in the slots l⁵ in the side plates L, as heretofore de- 30 scribed. The peculiar shape and disposition of the two cam-plates M and the pinions N effect a locking of the parts at any point to which they may be returned, as will be readily understood. 35

40 I may, if desired, utilize the device illustrated in Fig. 3 for locking the parts in position when adjusted to maintain the leaves in a desired adjustment. This device may or may not be used in connection with the means for effecting this already described. 45 The construction of such locking device may be as follows: The hubs or collars i¹ of the arms i², encircling rods i³, may be provided on their under surface with outward-facing ratchet-serrations i⁴, engaged by pawls i⁵, as spring-pawls, and plungers i⁶ may be provided for disengaging the pawls. It will be obvious that by this arrangement either pawl will operate to prevent the depression of the book-supporting leaf on that side. 55

It is to be understood that I do not wish to be limited to the use of teeth in the hub or collar and of a pawl working therein, as other equivalent forms of device may be utilized 60 to subserve a like function, such as a device consisting of a band passing around the collar and to be drawn into frictional contact therewith in any preferred manner, as by thumb-screws or by levers, &c. By the arrangement here set forth a very important

result is effected—namely, in having the book-support capable of being determinately adjusted with relation to the platen, and this function is effected through the medium of the cam-plates, pinions, and locking and other mechanisms adjunctive thereto. 70

The operation of this mechanism will be obvious. When a book is placed upon the book-rest, the leaves J, J² thereof will generally be at the highest point or even with the under side of the platen. The cam-plates M, resting in contact with the pinions N, upon being moved, the pin l⁶, carrying the rocking plate K, is forced to the top of the slot l⁵ in the plates L, as shown in Fig. 4. Where the yielding leaves J, J² are not in horizontal alinement, they are preferably brought into this position. The platen being raised, the open book is laid on the book-support, one cover on each of the supporting-leaves, and the platen is swung down into position over one side of the book. If the book be so thick as to necessitate a forcible depression of the underlying half of the book by the platen, the hand-wheel n³ may be turned to rotate 90 the pinions N to cause the cam-plates M to turn in the proper direction. These in turn cause the pin l⁶ to lower, and with it the rocking plate K. This imparts a downward motion to the leaves J, J² and their supporting 95 mechanism. At the point where the platen may rest upon the front portion of the table or upon a standard provided therein the turning of the hand-wheel n³ is ceased. By reason of their construction, disposition, and operation the cam-plates and pinions are practically self-locking to hold the parts in this adjusted position as long as desired. It will be understood, of course, that the weight of the book-supporting leaves and the superimposed book are sufficient to keep the cam-plates at all times in engagement with their meshing pinions. If a smaller book is then to be written in, the hand-wheel n³ should be rotated in the opposite direction to cause the leaves to be raised until the book presses under the platen. During operation of the book-support, it may be observed, rocking plate K serves, by reason of the cam-plates and pinions, as a vertically-adjustable 100 support for the rising and falling book-supporting leaves, while the parallel arms i² i² may be regarded as means for guiding the leaves in their rising and falling movements, or since the vertical adjustment of plate B 105 is at once communicated through standards i⁶ to said parallel arms the plate and arms may together be regarded as constituting a vertically-adjustable support for the leaves, which are themselves capable of vertical movement. A feature of this construction is that when the parts are once adjusted for a particular size of book it remains in this adjustment until it becomes necessary to change it for a different size of book. The 110 115 120 125 130

construction, disposition, and operation of the rocking plate K adjust the mechanism for various thicknesses of half of the book as leaves are turned in the progress of the work. There is here, therefore, an automatically-adjusting table. It is to be understood that the rocking plate K and its adjusting mechanism may be omitted and yet the table will accomplish the desired results, but necessarily to a more limited extent, since it would not accommodate books of extra thickness. To facilitate the operation of the parts when the book has been placed upon the book-rest and it is desired to regulate the position of the leaves carrying the book-covers, the wheel n^3 on the rod n^2 is turned in the proper position, which causes the double pinion N to rotate to move the double cam-plate M, which operation raises or lowers the standard i^6 and its leaf J or J^2 , as the case may be, as already described. When the desired adjustment has been effected, the clutch-knob n^4 on the end of the rod n^2 may be utilized to lock the parts until occasion requires a change of plane of the leaves J and J^2 for a different size of book than that just used. Said clutch-knob n^4 is mounted on the screw-threaded end of a spindle n^{14} , which passes longitudinally through the rod n^2 and is provided at its other end with a disk n^{15} , bearing against the outside of the rear plate L. It is obvious that the rod n^2 may be clamped in place by rotating the clutch-knob in the proper direction. However, the frictional engagement of the cam-plates M and the pinions N may ordinarily be depended upon to retain the book-rest at the desired height. It is preferable to dispose of the parts for supporting the leaves J and J^2 toward their rear. Otherwise they would strike the back of the book when in certain positions, and this disposition also economizes space. The parallel arms supporting the standards tend to distribute the weight evenly, so that the rocking plate and cam-plates bear little or no more strain than the rest and keep the leaves in perfect horizontal plane and particularly when they are being adjusted.

The device just described is what I term an "adjustable" book-rest to facilitate the vertical adjustment of the leaves J and J^2 to bring one or the other to a desired plane. By the same I produce a "parallel-motion" device, permitting the book-rest as a whole to rise or fall, but keeping it constantly in its horizontal position. It is to be understood that any equivalent construction and arrangement of parts which will permit the rise and fall may be utilized (such as that shown in my pending application, Serial No. 64,890) and yet be within the spirit of my invention.

The parts are made of such strength and are so adjusted that the leaves J J^2 will carry

the weight of any book which may be laid upon them. The fact that the two leaves may rise and fall interdependently admits of the leaves on opposite sides being brought to the same horizontal plane or, in other words, to the same level regardless of the point at which the book may be opened—that is to say, regardless of the fact that there may be a greater thickness of leaves on one side than on the other. 75

By reason of the vertical adjustability of the book-support B and of the longitudinal movement of its base-frame B² the book in which the printing is to be effected may easily be shifted to the right or left in order to bring one side or the other of the book into the field of action of the writing mechanism and then adjusted vertically to present the writing-surface to a proper plane for action. The book-support remains at rest during the writing operation. It is of course understood that the two leaves forming the book-rest may be capable of rising and falling independently and be maintained at all times in a horizontal or approximately horizontal position. This leveling of the open book and sliding of the book-support are matters of decided advantage and convenience in the operation of the type-writer. 85

In devices heretofore employed and where in are used springs to keep the yielding leaves against the book each leaf operates independently of the other, so that there is always danger of the side of the book not under the platen being forced above the platen. 90 Moreover, the springs cannot possibly be of a kind to act the same with a light book as with a heavy one. In my device by having a parallel motion of the leaves through the medium of the rocking plate the top surfaces of the leaves are kept perfectly level always, and the weight of the book makes no difference in the effective working of the device. When once it has been adjusted for a particular book, it requires no further adjustment 100 for books of that particular kind. It is to be understood, of course, that this mechanism may be mounted upon the top of a desk by having the rectangular frame B² depressed in a suitably-channelled supplemental frame or box. The same would not in this instance necessarily be a permanent part of the desk or table. It is to be understood also that my sliding-top table may be utilized for sustaining large books—such as books of record, ledgers, dictionaries, and the like—where writing mechanism is not to be employed. Likewise equivalent devices for effecting movement and adjustment of the parts may be utilized without departing from the spirit 115 of my invention. 120

D represents a platen of metal preferably flat and rigid and hinged at one end on a horizontal rod d, fixed in standards or other supports d', attached to the table, so that the 130

platens may be turned upward to facilitate the adjustment of the book thereunder and then turned downward on the underlying side of the book, so that the leaf to be printed upon may be laid over and supported upon the upper surface of the platen.

In order to limit the downward motion of the platen and to sustain it normally in a horizontal position or position parallel with the underlying leaf-support, it may be made sufficiently large to rest upon the front edge of the table. The platen may be fixed in position; but when hinged, as at the rear, it permits the book and the leaf to be more conveniently adjusted in relation thereto.

In order to relieve the operator of the labor of lifting the platen, which may be of a large size and quite heavy, I propose to use a counterbalancing-spring, preferably made in the form shown at E, Figs. 1 and 2, in which it will be seen that the spring has one end attached to the platen and the other to the rod d. This spring exerts a constant upward pressure on the platen, and when made of sufficient strength it will serve to lift the platen and maintain it in an elevated position, as shown in Fig. 2, thus leaving the hands of the operator free for the manipulation of the adjustment.

As shown in Fig. 2, the platen may be provided at its front with means for maintaining it in a horizontal position against the action of the spring at the rear. This may be accomplished by any preferred form of catch d², taking upon a part of the table-top. At the rear of the platen I may utilize the top strip of the table A for attaching means, such as clamps, for holding manifolding material or the paper being written upon. I may also, if desired, cut away a portion of the top of the table at its rear and provide the edges thus produced with rollers over which may pass paper or manifolding material suitably suspended under or adjacent to the table-top. I may also, if desired, locate there guides for keeping the paper straight when feeding over to and upon the platen, all as illustrated in my copending application, Serial No. 76,142.

F designates the tracks, lying longitudinally of the table and parallel to the sides of the platen. These may be connected together at the front and rear and be suitably hinged at the rear of the table, as on a rod extending from track to track. At the front I may provide a suitable form of retaining device e to hold the tracks down upon the table, either a single one or a separate one for each track. The united tracks constitute a frame, which upon being lowered to its normal position around or upon the platen may be utilized to hold the work down upon the platen. These tracks support the writing mechanism G. When this writing mechanism is pushed back by the operator and the catches e at the front are released, the tracks

will lift on their hinges by the weight of the machine, or a weight or other device may if necessary or desired, be employed for lifting the tracks.

If desired, the rear ends of the tracks may extend back beyond the line of the table and be provided with abutments, the tracks being hinged or fulcrumed a suitable distance from their ends. This will permit the writing mechanism to be pushed back beyond the hinge or fulcrum point of the tracks, so that when it is desired to raise the tracks or frame up out of the way, the writing mechanism being at the extremities of the tracks, by merely releasing the retaining device e at the front the tracks or frame will, by reason of the weight of the writing mechanism thereon beyond their fulcrum-point, be caused to lift. The raising of the same may, if desired, be facilitated by providing springs or weights in a position to effect this result. When the writing mechanism is thus pushed back to the end of the tracks, it leaves the table free and open, so that the leaves of the book, the platen, or other work may be adjusted. Another important feature is that the tracks, (hereinafter described,) which preferably lie alongside of the edges of the platen and are independent thereof, do not have to be raised whenever it becomes necessary to raise the platen or to adjust the leaves of the book. They are likewise so disposed above the plane of the book-leaves that when the book is moved from one side of the table to the other they will not interfere with the book. It is to be understood, however, that the tracks may be raised upon the platen and serve to hold the work thereon and also to hold the platen down in place.

The construction of the writing mechanism, the platen, &c., is preferably the same as disclosed in my pending application, Serial No. 64,890.

In the operation of the machine herein described the tracks supporting the writing mechanism and the platen are both turned up out of the way. A book opened at any desired point or closed is then laid upon the leaves of the traveling support and the support is shifted to the right or left, as required, in order to permit the leaf to be printed upon to be brought in proper position. The platen is then turned down on the body of the book and the leaf to be written upon turned over upon the platen and the tracks lowered to bring the writing mechanism in proper position. Although the spring E is of sufficient weight to lift the platen, the weight of the overlying base-frame when made to rest upon the platen may be utilized to keep it down in operative position. If not, I may provide a suitable locking device, as already described. The spring may, however, be made weaker, so that the platen will be just heavy enough to rest horizontally, requiring little or no

lifting power to raise the platen to an angle of forty-five degrees, more or less. When in this position, the weight is thrown upon the hinges at the rear of the platen instead of being disposed at the front end of the platen, thus facilitating raising of the platen by the operator. In lieu of springs I may employ weights suitably disposed to subserve this function. When the writing on one page is completed, the machine on the tracks is moved back and the platen is lifted. Then the book-supporting frame is moved to the opposite side of the table and the platen is lowered, thus bringing the other side of the book beneath the platen, after which the other side of the leaf or the next leaf, as the case may be, is placed in position and the platen placed as before. It is not necessary, as before stated, to raise the tracks. The book-leaf may be held down by clamps or other retaining mechanism, and these may also be employed where separate sheets of paper, cards, &c., are to be written upon. When the vertically-adjustable and laterally-movable book-support is used, a vertical adjustment of the platen and base-frame in relation to the table or other support is unnecessary. The platen, frame, and writing mechanism are preferably so disposed as to be relatively at fixed heights.

It is to be observed that by the employment of the device described it is rendered possible for the operator to adjust a book of any size and weight quickly and easily in the proper relation to the platen and the writing mechanism. It is not necessary for the operator to lift the book after it is placed on the machine. As all the parts above the book can be turned up out of the way and are self-supporting, both hands may be used in the adjustment of the book. When the platen is turned down, it has the effect of depressing the underlying side of the book to the required level. After the platen is thus adjusted the leaf to be printed upon may be turned over upon it, adjusted in position, and, if desired, secured by turning down the upper frame, or this may be accomplished by clamping devices, as already described. It is to be observed that during all these operations the two hands of the operator are free for the purpose of adjusting the book and that without disturbing the book access may be had instantly to any part of the page for correction or other purposes. It is to be observed also that the arrangement shown does not necessitate any vertical adjustment of the parts supporting the writing mechanism and platen and that it does not require any provision for the lateral adjustment of these parts. For these reasons I am enabled to construct the machine cheaply and to give the parts extreme rigidity.

It is to be understood that I may, if desired, with the same elements constituting my sliding-top table make the same capable of

movement longitudinally instead of transversely by changing the direction of the channel *a* in the table and the position of the rollers on the same. Furthermore, I may, if desired, merely by combining these two constructions provide a construction by which the same may be moved both transversely and longitudinally. A supplemental base-frame and channel might be provided to constitute the construction for the longitudinally-movable device and this to carry the transversely-movable device, as shown in Fig. 10, and, finally, I could have means for effecting vertical adjustment of the table-top.

Having thus fully described my invention, what I claim as new, and desire to secure by Letters Patent, is—

1. In a book type-writer, the combination with a suitable base, and the flat platen and track-rails, of rising and falling book-supporting leaves underlying the platen, and a support member for said leaves supported by the base independently of the leaves and vertically adjustable to elevate or depress the leaves simultaneously.

2. In a book type-writer, the combination with the flat platen and track-rails, of rising and falling book-supporting leaves underlying the platen, and laterally-adjustable supporting means for said leaves, said means being also vertically adjustable to elevate or depress the leaves simultaneously.

3. In a book type-writer, the combination with a suitable base, and the flat platen and track-rails, of book-supporting leaves underlying the platen and connected together so as to move in opposite vertical directions, and common supporting means for said leaves supported by the base independently of the leaves and vertically adjustable to elevate or depress the leaves simultaneously.

4. In a book type-writer, the combination with a suitable base, and the flat platen and track-rails, of rising and falling book-supporting leaves underlying the platen, guiding means for said leaves, a common support member for said leaves vertically adjustable to elevate or depress the leaves simultaneously, and means whereby said member is supported by the base independently of the leaves.

5. In a book type-writer, the combination with a suitable base, and the flat platen and track-rails, of book-supporting leaves underlying the platen and connected together so as to move in opposite directions, guiding members pivoted to the leaves and base, and supporting means for the leaves distinct from said guiding members and vertically adjustable to elevate or depress the leaves simultaneously.

6. In a book type-writer, the combination with a suitable base, and the flat platen and track-rails, of book-supporting leaves underlying the platen, a rocking member connect-

- ing said leaves and pivotally supported intermediate its length by said base independent of the leaves, and means for simultaneously elevating or depressing the leaves.
5. In a book type-writer, the combination with a suitable base, and the flat platen and track-rails, of book-supporting leaves underlying the platen, parallel guiding and supporting arms pivoted to each leaf and to the base, a rocking member connecting said leaves and pivotally supported by said base intermediate its length, and means for vertically shifting the paths of travel thereof.
8. In a book type-writer, the combination with the flat platen and track-rails, of book-supporting leaves underlying the platen, a rocking member connecting said leaves and pivotally supported intermediate its length, and means for vertically adjusting said member.
9. In a book type-writer, the combination with the flat platen and track-rails, of book-supporting leaves underlying the platen, parallel guiding and supporting arms for each leaf, a rocking member connecting said leaves and pivotally supported intermediate its length, and means for vertically adjusting said member.
10. In a book type-writer, the combination with the flat platen and track-rails, of book-supporting leaves underlying the platen, a vertically-adjustable rocking member connecting said leaves, and a laterally-shiftable carriage in which said member is pivotally supported intermediate its length.
11. In a book type-writer, the combination with a suitable base, and the flat platen and track-rails, of book-supporting leaves underlying the platen and mounted so as to move in opposite vertical directions under the changing weights of the two sides of a superimposed book, common supporting means for said leaves supported by the base independently of the leaves, and means for vertically adjusting and maintaining said supporting means to elevate or depress the leaves simultaneously.
12. In a book type-writer, the combination with a suitable base, and the flat platen and track-rails, of book-supporting leaves underlying the platen and mounted so as to move in opposite vertical directions under the changing weights of the two sides of the superimposed book, a common support for said leaves supported by the base independently of the leaves, means for vertically adjusting said support to elevate or depress the leaves simultaneously, and means for locking the support at the desired elevation.
13. In a book type-writer, the combination with the flat platen and track-rails, of rising and falling book-supporting leaves underlying the platen, and a cam-plate for adjusting the height at which the leaves operate.
14. In a book type-writer, the combination with the platen and track-rails; of book-supporting leaves underlying the platen, a rocking member connecting said leaves, a pivot for said member, and a cam-plate carrying said pivot.
15. In a book type-writer, the combination with the flat platen and track-rails, of book-supporting leaves underlying the platen, a rocking member connecting said leaves, a pivot for said member, a vertically-movable vertical cam-plate carrying said pivot, and means for rotating said cam-plate.
16. In a book type-writer, the combination with the flat platen and track-rails, of book-supporting leaves underlying the platen, a rocking member connecting said leaves, a pivot for said member, and two rotatable adjusting members comprising a cam-plate and an engaging member, one being mounted in fixed bearings and the other for vertical movement and carrying said pivot.
17. In a book type-writer, the combination with a flat platen and the track-rails, of book-supporting leaves underlying the platen, a rocking member connecting said leaves, a pivot for said member, and two rotatable adjusting members comprising a toothed cam-plate and an engaging pinion, one being mounted in fixed bearings and the other for vertical movement and carrying said pivot.
18. In a book type-writer, the combination with the flat platen and track-rails, of book-supporting leaves underlying the platen, a rocking member connecting said leaves and having its pivot extending laterally, a vertically-slotted support, and two rotatable adjusting members comprising a cam-plate and an engaging member, one being mounted in fixed bearings in said support and the other for vertical movement therein, having the pivot of the rocking member passing therethrough and within the slot in the support.
19. In a book type-writer, the combination with the flat platen and track-rails, of rising and falling book-supporting leaves underlying the platen, and upward-extending parallel supporting and guiding arms beneath each leaf, one arm beneath the forward portion of the leaf and two arms beneath the rear portion thereof.
20. In a book type-writer, the combination with the flat platen and track-rails, of rising and falling book-supporting leaves underlying the platen, and upward-extending supporting and guiding arms beneath each leaf, one arm immediately beneath the forward portion of the leaf and two superposed arms beneath the rear portion thereof.
21. In a book type-writer, the combination with the flat platen and track-rails, of rising and falling book-supporting leaves underlying the platen, a short standard depending from the forward portion of each leaf, a long standard depending from the rear portion thereof, a single supporting and guid-

ing arm pivoted to each short standard, and two parallel supporting and guiding arms pivoted to each long standard.

22. In a book type-writer, the combination with the flat platen and track-rails, of rising and falling book-supporting leaves underlying the platen, a supporting-frame, and upwardly and inwardly extending parallel guiding and supporting arms pivoted at their outer ends to each end of said frame and at their outer ends pivoted to and carrying said leaves.

23. In a book type-writer, the combination with the flat platen and track-rails, of rising and falling book-supporting leaves underlying the platen, a rocking member connecting said leaves, and upward-extending parallel supporting and guiding arms beneath each leaf, one arm immediately beneath the forward portion of the leaf and two superposed arms beneath the rear portion thereof.

24. In a book type-writer, the combination with the flat platen and track-rails, of rising and falling book-supporting leaves underlying the platen, a laterally-shiftable support, a rocking member connecting said leaves and pivoted to the middle of said support, and upwardly and inwardly extending parallel supporting and guiding arms pivoted to each end of said support and carrying the leaves.

25. In a book type-writer, the combination of a table, a platen mounted at a distance above the table, a track-frame lying above the platen and swinging upward independently thereof, the tracks of the frame extending sufficiently beyond their hinged or fulcrumed point to afford a rest region in rear thereof, and a downward-acting writing mechanism carried by the frame and movable longitudinally and laterally thereover and positionable on said rest region to overbalance the forward region of the frame.

26. In a book type-writer, the combination with a book-support, consisting of vertically-movable leaves, standards thereon, pivotally-mounted supporting-arms pivoted to said standards, the arms for each leaf being in parallel disposition and inclined upward, and a rocking plate connecting the leaves for simultaneous movement, of a platen, and means for supporting the same, substantially as described.

27. In a book type-writer, the combination with a book-support, consisting of vertically-movable leaves, standards thereon, the standards being sustained by parallel supporting-arms, there being a single arm at the front of each leaf and two at the rear, the arms being so disposed as to maintain the leaves in horizontal plane, of a platen and means for supporting the same, substantially as described.

28. In a book type-writer, the combina-

tion with a book-support, consisting of vertically-movable leaves, standards thereon, pivotally-mounted supporting-arms pivotally secured to said standards, the supporting-arms for the two leaves being unconnected and so adjusted as to maintain the leaves in a horizontal plane, connecting standards on the opposing leaves, a rocking plate, means for actuating the rocking plate and maintaining the same in any desired position, of a platen, and means for supporting the same, substantially as described.

29. In a book type-writer, the combination with a book-support, consisting of vertically-movable leaves, standards thereon, pivotally-mounted supporting-arms pivotally secured to said standards, a rocking plate connecting standards on the opposed leaves, a cam-plate and pinion operating in conjunction with the rocking plate to position 85 elevate or depress the yielding leaves, of a platen, and means for supporting the same, substantially as described.

30. In a book type-writer, the combination with a book-support, consisting of leaves, vertically-movable standards thereon, pivotally-mounted supporting-arms pivotally secured to said standards, a rocking plate connecting standards on the opposite leaves, a cam-plate and pinion operating in conjunction with the rocking plate to position 90 elevate or depress the yielding leaves, means for maintaining the cam-plate and pinion in the desired adjusted position, of a platen, and means for supporting the same, substantially as de- 100

31. In a book type-writer, the combination with a book-support, consisting of vertically-movable leaves, standards thereon, pivotally-mounted supporting arms pivotally secured to said standards, the arms carrying means for locking them in any desired position, a rocking plate connecting standards on the opposed leaves, a cam-plate and pinion operating in conjunction with the rocking plate to position 105 elevate or depress the yielding leaves, means for maintaining the cam-plate and pinion in the desired adjusted position, of a platen, and means for supporting the same, substantially as described.

32. In a book type-writer, the combination with a book-support, consisting of leaves movingly and yieldingly disposed and carried by standards sustained by arms, a rocking plate connecting the standards, cam-plates and pinions operating in conjunction with the rocking plate to position the yielding leaves to operate to effect locking of the parts, of a platen, and means for supporting the same, substantially as described.

33. In a book type-writer, the combination with a book-support consisting of leaves movingly and yieldingly disposed and carried by standards sustained by arms, a rocking plate, cam-plates and pinions operating 120

125

130

in conjunction with the rocking plate to position the yielding leaves, retaining devices operating upon the sustaining-arms for maintaining and locking the leaves in position, 5 when adjusted, of a platen, and means for supporting the same, substantially as described.

34. In a book type-writer, the combination of a book-support consisting of leaves 10 movingly and yieldingly disposed and carried by front and rear standards sustained by arms, the front standards being shorter than those at the rear, and mechanism for raising and lowering the standards consisting of 15 cam-plates and pinions, a rocking plate connecting with the cam-plates and pinions, of a platen and means for sustaining the same, substantially as described.

35. In a book type-writer, the combination 20 of a book-support consisting of leaves movingly and yieldingly disposed and carried by front and rear standards, a pair of parallel arms sustaining each rear standard, and a single arm for sustaining each of the front 25 standards, of a platen and means for supporting the same, substantially as described.

36. In a type-writer, the combination of a 30 table, a platen mounted at a fixed distance above the table, a horizontally - shiftable book-support comprising oppositely-moving rising and falling leaves, and means for adjusting the elevation of the whole book-support in order to permit free horizontal movement of the support beneath the platen.

37. In a type-writer the flat platen in combination with the pivoted paper-confining frame, and the writing mechanism arranged to traverse and pass beyond the pivot for the purpose of automatically elevating the forward end of the frame.

38. In a book-type-writer, the combination 40 with an adjustable book-support, of overlying one-piece track-rails pivoted intermediate their length to present a forward work region and a rear region capable of receiving an imposed traveling writing mechanism to facilitate the tilting of the track-rails away from the book-support.

39. In a book type-writer, the combination 45 with one-piece track-rails pivoted inter-

mediate their length to present front and rear machine-supporting regions, and a traveling machine capable of occupying either region; of an adjustable book-support underlying the front track region.

55

40. In a book type-writer, the combination with one-piece track-rails pivoted intermediate their length to present front and rear machine-supporting regions, and a traveling machine capable of occupying either 60 region to assist in positioning the track-rails; of an adjustable book-support underlying the front track region and including rising and falling leaves adapted to receive books of varying thickness.

65

41. In a book type-writer, the combination with an adjustable book-support, of overlying one-piece track-rails pivoted intermediate their length to present front and rear machine-supporting regions, a traveling 70 machine capable of occupying the rear track region to facilitate tilting of the track-rails away from the book-support, and a lock for securing the rails in position above the book-support.

75

42. In a book type-writer, the combination with a tiltable flat platen, one-piece track-rails at either side, and free of said platen and pivoted intermediate their length to present front and rear machine-supporting regions, and an adjustable book-support underlying said platen and rails; of means for locking the platen in position over the book-support, and distinct means for locking the rails in operative position.

85

43. In a type-writer, the combination with one-piece track-rails pivoted intermediate their length to present front and rear machine-supporting regions, and a traveling machine capable of occupying either region 90 to assist in positioning the track-rails, of a lock for securing the rails in horizontal position against the counterbalancing action of the machine.

In testimony whereof I affix my signature 95 in the presence of two subscribing witnesses.

GEORGE W. DONNING.
